(57) **CLAIM**

The ornamental design for a water bottle grip, as shown and described.

DESCRIPTION

FIG. 1 is a perspective view of a water bottle grip;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a bottom plan view thereof;

FIG. 7 is a top plan view thereof; and,

FIG. 8 is a front view thereof attached to a water bottle.

The broken line showing of a water bottle in FIG. 8 is for the purpose of illustrating environmental structure and forms no part of the claimed design.
